Primary Examiner — Cynthia Ramirez(57) **CLAIM**

The ornamental design for a cart with lifting rack, as shown and described.

DESCRIPTION

FIG. 1 is a perspective view of a cart with lifting rack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 2. The dash-dash broken lines in the drawings depict portions of the cart with lifting rack that form no part of the claimed design. The dot-dash broken lines represent boundaries of the enlarged portions and form no part of the claimed design.
